US00D695231S

(12) **United States Design Patent**
Shen

(10) **Patent No.:** US D695,231 S
(45) **Date of Patent:** ** Dec. 10, 2013

(54) **OVERCURRENT PROTECTION
CIRCUIT-BREAKER**

(76) Inventor: **Jixun Shen, Zhejiang (CN)**

(**) Term: **14 Years**

(21) Appl. No.: **29/423,412**

(22) Filed: **May 31, 2012**

(30) **Foreign Application Priority Data**

Apr. 28, 2012 (CN) 2012 3 0139821

(51) **LOC (9) Cl.** 13-03

(52) **U.S. Cl.**

USPC **D13/160**

(58) **Field of Classification Search**

USPC D13/158, 159, 160, 161, 162, 169;
200/43.14, 50.01, 50.21–50.23, 51 R,

(57) **CLAIM**

The ornamental design for an overcurrent protection circuit-breaker, as shown and described.

DESCRIPTION

FIG. 1 is a left front perspective view of an overcurrent protection circuit-breaker showing my new design;
FIG. 2 is a front elevation view thereof;
FIG. 3 is a rear elevation view thereof;
FIG. 4 is a left side elevation view thereof;
FIG. 5 is a right side elevation view thereof;
FIG. 6 is a top plan view thereof; and,
FIG. 7 is a bottom plan view thereof.
